UNITED STATES PATENT OFFICE.

ANDREW FORSTER, OF COWES, ENGLAND, ASSIGNOR TO J. SAMUEL WHITE & COMPANY LIMITED, OF EAST COWES, ISLE OF WIGHT, ENGLAND.

APPARATUS FOR USE IN THE BURNING OF LIQUID FUEL.

Application filed December 14, 1920. Serial No. 430,732.

To all whom it may concern:

Be it known that I, ANDREW FORSTER, a subject of the King of England, and residing at Cowes, Isle of Wight, England, have 5 invented certain new and useful Improvements in Apparatus for Use in the Burning of Liquid Fuel, of which the following is a specification.

This invention relates to apparatus for 10 use in the burning of liquid fuel and has for its object to enable substantially perfect combustion of the fuel to be obtained while the apparatus itself is designed so that it can be constructed cheaply.

15 In applying burners for liquid fuel to steam generators it is desirable to arrange the sprayer within a casing which can be readily mounted on the generator the construction of the casing being preferably simple and cheap. The casing must have openings with suitable means for controlling them in order to allow of the ignition of the air necessary for combustion. Such apparatus as previously constructed has tended 20 to be cumbersome and expensive to make while further the means by which the air is admitted and controlled and the disposition of the sprayer did not permit of the combustion being so regulated as to always 25 ensure that this combustion was complete.

According to this invention the fuel sprayer is mounted in or at one end of a 30 conical member so that the flame from the sprayer will impinge on the inner surface 35 of the cone. A conical casing forming an air box surrounds the cone and has in its wall openings through which air can enter in such a manner as to strike on or pass over the heated cone. The size of the air inlet 40 openings is adjusted or these openings can be closed by means of a rotatable or sliding shutter mounted on the casing. The outer end of this casing is closed by a plate which carries the coned member and the sprayer 45 and in this plate are openings adapted to be controlled by a movable shutter. As the air enters the casing through the openings in the wall thereof it will strike on and pass over the exterior of the cone which is maintained in a considerably heated state by 50 the flame within it. The amount of air which enters the casing can be accurately adjusted by means of the shutter which is preferably conical and rotatable and is car-

ried on the casing and movable over the 55 openings therein. An outer casing preferably conical may be mounted on the air box and so arranged that air will enter this outer casing near the wall of the steam generator to which the air box is fixed. 60 The air will thus receive a preliminary heating from the generator wall and will then pass into the air box and over the heated cone which will cause the air to be still further heated before it enters the 65 combustion chamber. Air can also enter the air box through the openings in the end plate around the sprayer, the air thus admitted passing into the cone member. The outer casing may conveniently be arranged to communicate with a jacket which wholly or partially surrounds the uptake 70 so that the air can receive heat from the uptake before it enters the air box.

In order to simplify the construction of 75 the air box this may be formed with an annular step at some point in its length the depth of this step being not less than the thickness of the wall of the casing. The 80 openings in the casing then extend through the wall thereof from the step to the smaller end of the conical casing. On this part of the casing between the step and the end of it is mounted a conical shutter which can be rotated on the casing and by means of 85 which the size of the openings can be regulated. If as is convenient the casing is formed by casting, the casting process is simplified by this formation since no core 90 is needed as there are no parts which project in such a way as to prevent the removal of the casting from the conical mould. The casing thus formed has the appearance of a cone whose smaller end is composed of a series of separated strips or fingers. 95

In a modified construction the conical member is mounted on the end of a cylindrical part immediately surrounding the nozzle of the sprayer and in this cylindrical part are air inlet openings which are controlled by a cylindrical shutter which is preferably connected to the shutter which controls the openings in the end plate or air box. The cylindrical part of the conical member is also mounted in the cylindrical 100 shutter so that it can slide in or out of this shutter whereby the position of the conical 105 portion of the member with relation to the

nozzle can be adjusted and at the same time the longitudinal dimensions of the air inlet openings through the cylindrical part of this member can be varied. The sliding adjustment of the conical member is effected by means of one or more screw or like devices which are carried out through the end plate of the air box.

In either construction the opening in the generator wall may be provided with an annular lining of fire brick whose inner edge is conveniently V-shaped in cross section or bevelled off in both directions. This lining is arranged so that one bevelled part lies substantially in line with the larger end of the conical member the other inclined edge forming one side of an annular opening through which air can enter between the end of the conical member and the fire brick lining. Around and on the outer side of the opening in which is placed this lining is an annular plate which is bolted up in position between the wall of the generator and the air box. The dimensions of the whole opening opposite which the air box is mounted may be adjusted by employing interchangeable plates having openings in them of different sizes the size of the fire brick lining of the opening being altered accordingly.

The invention may be carried out in practice in various ways and the details of construction modified to suit requirements but the accompanying drawings illustrate by way of example two alternative constructions that may be adopted for use with a steam generator of the water tube type. In these drawings—

Figure 1 is a vertical sectional elevation through one construction of the improved air box and sprayer mounting.

Figure 2 is an end view of the same.

Figure 3 is a sectional elevation similar to Figure 1 of an alternative construction and

Figure 4 is an end view of the same.

Like letters indicate like parts throughout the drawings.

Referring to the construction illustrated in Figures 1 and 2 the casing A forming the air box is flanged at one end as at A' and bolted to the casing B of the steam generator around the opening C leading into the furnace or combustion chamber. The casing A is conical with the flange A' formed at the larger end and it has an annular step A² or break in its external surface at a point which as shown is not far distant from the largest end of the box. In the wall of the air box and extending from the step A² to the smaller end thereof are a series of openings A³ which are conveniently rectangular and extend longitudinally through the wall of the box. Since the depth of the step A² is preferably equal to the thickness of the wall of the casing A the external surface of the smaller part of

the casing in which are the openings A³ when viewed in longitudinal section as in Figure 1 lies, as is apparent in that figure, substantially in line with the interior surface of the larger end of the casing adjacent to the flange A'. Hence it will be seen that the casting of the casing A and the openings A³ therein can be simplified by reason of the fact that a simple conical mould formed in the top box may be used without the necessity of providing projecting parts or cores for the openings A³. The air openings A³ are regulated by means of a shutter D formed as a cast cone which fits on the smaller part of the casing A and extends from the step A² to the end of the casing. Openings D' are formed through the wall of the shutter which can be rotated on the casing A and these openings D' are of such dimensions and so spaced apart that by movement of the shutter in relation to the openings A³ the air passages through the casing A can be regulated or these openings can be completely closed.

At or within the smaller end of the casing A is mounted a disc or plate E in which are openings E'. The sprayer, which is not shown in this figure, is mounted in an opening E² formed in a boss E³ at the centre of the disc E and a shutter F of suitable form is carried on the boss E². In the shutter F are openings corresponding to the openings E' in the disc E so that by rotation of the shutter F which can be effected by means of a handle F' the effective size of the openings E' can be regulated or these openings can be closed. The end plate E is bolted up to an inwardly directed flange A⁴ at the smaller end of the conical air box casing A. On the inner side of the end plate E is mounted a cone G which thus lies within the air box A and is so positioned in relation to the end or nozzle of the sprayer that the cone of liquid fuel as it issues from the sprayer will impinge on the inner surface of the conical member G preferably at or not far from the larger end of this cone. The cone G is supported by three screwed studs H which extend from the smaller end of the cone through the end plate E in which these studs are fixed by nuts in such a manner that the position of the cone G in relation to the sprayer nozzle and the end plate E can be adjusted.

On the smaller end of the air box casing A or, as in the construction illustrated, on the peripheral part of the end plate E is mounted an outer conical or other casing J whose length is such that it will extend over and around the air box A for a considerable portion of the length of the latter. The air which enters the air box must thus have access thereto through the annular space formed between the end of the casing J and the adjacent wall B of the steam generator. In some cases the outer casing J may be ex-

tended towards the steam generator wall B and carried up at a distance from this wall but parallel thereto so as to form a jacket over the generator wall. This construction 5 is shown in dotted lines at J' in Figure 1. The air which enters the air box A then has to pass first through this jacket around the uptake and over the wall of the steam generator to the openings A² in the air box. 10 Thence the air travels over the exterior of the cone G which is maintained at a considerable heat by the flame within it and thus the temperature of the air is appreciably raised before it enters the combustion chamber. 15

The detailed construction of the shutters D and F controlling the air openings A² and E' and the manner in which these shutters are operated may be modified as found desirable. 20

Referring to the modified construction illustrated in Figures 3 and 4 in this case there is mounted in the opening C which leads into the combustion chamber or furnace of the steam generator a fire brick ring K which is conveniently built up of four pieces and has its inner edge bevelled off as at K' and K² in opposite directions as shown in Figure 3. Against the outer face of this 25 fire brick ring K is laid an asbestos sheet L and a plate M is then placed on the outside of the fire brick ring and bolted up to the steam generator casing B the plate M having in it a hole M' whose dimensions are determined by requirements. Alternative and 30 interchangeable plates M are provided for this purpose with holes in them of different dimensions. On the outside of the plate M is mounted the conical casing or air box A 35 which in respect to its principal features is constructed as in the apparatus described with reference to Figure 1, that is to say this air box has an external annular step A² and a conical shutter D with openings D' in it 40 by rotation of which on the air box casing A the dimensions of the air openings A² can be varied.

At the outer end of the air box A is fixed a plate E in which are openings E' disposed around a central boss E² having in it an opening E² through which passes the oil sprayer N the latter being fixed to the plate E. As in the previously described construction the dimensions of the air openings 45 through the end plate E can be varied by means of a rotatable shutter F disposed on the inner side of the plate E but in this construction there is formed or mounted on the inner side of the shutter F a cylindrical member F² in which are longitudinal openings F³ extending from the end of the cylindrical member towards the shutter F. This cylindrical member projects into the air box A around the nozzle N' of the sprayer. The 50 cone G is provided at its smaller end with a

cylindrical part G' which lies within the cylindrical member F² and has longitudinal openings formed in it as at G² similar to the openings F³. The cone G and its cylindrical part G₂ are carried in an adjustable manner on screwed studs H by the end plate E so that the cylindrical part G' lies within the cylindrical member F². The openings F³ and G² in these engaging parts are conveniently rectangular and of such substantial dimensions as shown in Figure 3 and it will be seen that the dimensions of the air passages formed by these openings can be varied by rotation of the shutter F and according to the position 70 of the cone G with respect to the end plate E and sprayer nozzle N'. The cylindrical part G' of the cone can thus slide or be moved longitudinally within the cylindrical member F² while the latter can be rotated around the part G'. 75

On the periphery of the end plate E or, if preferred on the smaller end of the conical air box casing A there is mounted a conical shield J as in the previously described construction, this shield conveniently having in it one or more observation or sighting openings J². The shield is arranged so as to lead air from the neighbourhood of the wall B of the steam generator to the openings A² 80 in the air box A. 90

In use air can enter through the end of the conical shield J whence it passes through the openings A² in the air box A which have been adjusted to the size required by 100 means of the shutter D. The air which is thus somewhat warmed can pass over the exterior of the cone G between the end thereof and the outer bevelled face K² of the fire brick lining K and through the opening C 105 leading into the combustion chamber. Air can also pass through the openings in the cylindrical part F² into the interior of the cone around the sprayer nozzle N' these openings having been adjusted to the required dimensions by rotation of the shutter F and cylindrical member F². The movement of this shutter also determines the amount of air passing through the openings E' in the end plate E. The position of the cone G has previously been adjusted in the axial direction by means of the studs H in accordance with requirements and the dimensions of the opening C leading into the combustion chamber. 110

In this case as in the construction described with reference to Figure 1 the outer conical shield J may be extended towards the wall B of the steam generator so that air which has been warmed by contact with 115 the wall of the generator will pass to the openings in the air box A. In this construction as in that previously described the formation of the parts is such that their casting can be effected in a simple manner 120 125 130

since moulding can be carried out without cores thus enabling the manufacturing cost to be decreased.

The details of construction may be modified as found desirable to meet requirements and in accordance with the type of steam generator to which the apparatus is applied.

What I claim as my invention and desire to secure by Letters Patent is:—

- 10 1. In apparatus for use in the burning of liquid fuel the combination of a conical casing forming an air box and having in its wall openings through which air can enter, means for adjusting the size of these openings, a conical shield mounted at the smaller end of the casing flaring toward the larger end of the casing and extending over the openings in the latter to cause the air to take an indirect course to the air openings, a fixed plate which closes the outer end of the casing and has air inlet openings therein, a rotatable shutter by means of which the size of these openings can be adjusted, a hollow conical member disposed within the casing and carried by the end plate at a distance therefrom, and a fuel sprayer mounted in the end plate as set forth.
- 20 2. In apparatus for use in the burning of liquid fuel the combination of a conical casing forming an air box and having in its wall openings through which air can enter, means for adjusting the size of these openings, a plate which closes the outer end of the casing and has air inlet openings therein, means for adjusting the size of these openings, a hollow conical member having at one end a cylindrical part with openings therein the member being disposed within the casing with its cylindrical part directed towards the end plate, means for supporting the conical member on the end plate, means for adjusting the size of the openings in the cylindrical part of the conical member, and a fuel sprayer mounted in the end plate as set forth.
- 30 3. In apparatus for use in the burning of liquid fuel the combination of a conical casing of substantially uniform thickness from end to end and forming an air box, said casting having an annular step in its wall intermediate its ends with openings through the part below the step through which air can enter, a conical shutter rotatably mounted on that portion of the casing which lies between the step and the smaller end thereof this shutter serving to adjust the size of the openings in the casing, a plate which closes the outer end of the casing having air inlet openings therein, means for adjusting the size of these openings, a hollow conical member disposed within the casing and carried by the end plate at a distance therefrom, and a fuel sprayer mounted in the end plate as set forth.
- 40 4. In apparatus for use in the burning of liquid fuel the combination of a conical casing forming an air box and having in its wall openings through which air can enter, means for adjusting the size of these openings, a fixed plate which closes the outer end of the casing and has air inlet openings therein, a rotatable shutter by means of which the size of these openings can be adjusted, a cylindrical member mounted on and rotatable with this shutter and projecting into the casing this member having openings in it, a hollow conical member having at one end a cylindrical part with openings therein the conical member being disposed within the casing with its cylindrical part lying within the cylindrical member carried by the rotatable shutter, means for supporting the conical member on the end plate, and a fuel sprayer mounted in the end plate as set forth.
- 50 5. In apparatus for use in the burning of liquid fuel the combination of a conical casing forming an air box and having in its wall openings through which air can enter, a conical shutter rotatably mounted on the casing and serving to adjust the size of the openings in the latter, a conical shield mounted at the smaller end of the casing and extending over the openings in the latter, a fixed plate which closes the outer end of the casing and has air inlet openings therein, a rotatable shutter by means of which the size of these openings can be adjusted, a hollow conical member disposed within the casing and carried by the end plate at a distance therefrom, a fuel sprayer mounted in the end plate in such a position that the spray therefrom impinges on the inner surface of the hollow conical member, and means for adjusting the position of the conical member relatively to the fuel sprayer and the casing, as set forth.
- 60 6. In apparatus for use in the burning of liquid fuel the combination of a conical casing forming an air box and having in its wall openings through which air can enter, a conical shutter rotatably mounted on the casing and serving to adjust the size of the openings in the latter, a conical shield mounted at the smaller end of the casing and extending over the openings in the latter, a fixed plate which closes the outer end of the casing and has air inlet openings therein, a rotatable shutter by means of which the size of these openings can be adjusted, a hollow conical member disposed within the casing and carried by the end plate at a distance therefrom, a fuel sprayer mounted in the end plate as set forth.
- 70 7. In apparatus for use in the burning of liquid fuel the combination of a conical casing forming an air box and having in its wall openings through which air can enter, means for adjusting the size of these openings, a fixed plate which closes the outer end of the casing and has air inlet openings therein, a hollow conical member having at one end a cylindrical part with openings therein the member being disposed within the casing with its cylindrical part directed towards the end plate, means for supporting the conical member on the end plate, means for simultaneously adjusting the size of the openings in the end plate and the size of the openings in the cylindrical part of the conical member, and a fuel sprayer mounted in the end plate as set forth.
- 80 8. In apparatus for use in the burning of liquid fuel the combination of a conical casing forming an air box and having in its wall openings through which air can enter, means for adjusting the size of these openings, a fixed plate which closes the outer end of the casing and has air inlet openings therein, a rotatable shutter by means of which the size of these openings can be adjusted, a cylindrical member mounted on and rotatable with this shutter and projecting into the casing this member having openings in it, a hollow conical member having at one end a cylindrical part with openings therein the conical member being disposed within the casing with its cylindrical part lying within the cylindrical member carried by the rotatable shutter, means for supporting the conical member on the end plate, and a fuel sprayer mounted in the end plate as set forth.
- 90 9. In apparatus for use in the burning of liquid fuel the combination of a conical casing forming an air box and having in its wall openings through which air can enter, a conical shutter rotatably mounted on the casing and serving to adjust the size of the openings in the latter, a conical shield mounted at the smaller end of the casing and extending over the openings in the latter, a fixed plate which closes the outer end of the casing and has air inlet openings therein, a rotatable shutter by means of which the size of these openings can be adjusted, a hollow conical member disposed within the casing and carried by the end plate at a distance therefrom, a fuel sprayer mounted in the end plate in such a position that the spray therefrom impinges on the inner surface of the hollow conical member, and means for adjusting the position of the conical member relatively to the fuel sprayer and the casing, as set forth.
- 100 10. In apparatus for use in the burning of liquid fuel the combination of a conical casing forming an air box and having in its wall openings through which air can enter, a conical shutter rotatably mounted on the casing and serving to adjust the size of the openings in the latter, a conical shield mounted at the smaller end of the casing and extending over the openings in the latter, a fixed plate which closes the outer end of the casing and has air inlet openings therein, a rotatable shutter by means of which the size of these openings can be adjusted, a cylindrical member mounted on and rotatable with this shutter and projecting into the casing this member having openings in it, a hollow conical member having at one end a cylindrical part with openings therein the conical member being disposed within the casing with its cylindrical part lying within the cylindrical member carried by the rotatable shutter, means for supporting the conical member on the end plate, and a fuel sprayer mounted in the end plate as set forth.
- 110 11. In apparatus for use in the burning of liquid fuel the combination of a conical casing forming an air box and having in its wall openings through which air can enter, a conical shutter rotatably mounted on the casing and serving to adjust the size of the openings in the latter, a conical shield mounted at the smaller end of the casing and extending over the openings in the latter, a fixed plate which closes the outer end of the casing and has air inlet openings therein, a rotatable shutter by means of which the size of these openings can be adjusted, a hollow conical member disposed within the casing and carried by the end plate at a distance therefrom, a fuel sprayer mounted in the end plate in such a position that the spray therefrom impinges on the inner surface of the hollow conical member, and means for adjusting the position of the conical member relatively to the fuel sprayer and the casing, as set forth.
- 120 12. In apparatus for use in the burning of liquid fuel the combination of a conical casing forming an air box and having in its wall openings through which air can enter, a conical shutter rotatably mounted on the casing and serving to adjust the size of the openings in the latter, a conical shield mounted at the smaller end of the casing and extending over the openings in the latter, a fixed plate which closes the outer end of the casing and has air inlet openings therein, a rotatable shutter by means of which the size of these openings can be adjusted, a cylindrical member mounted on and rotatable with this shutter and projecting into the casing this member having openings in it, a hollow conical member having at one end a cylindrical part with openings therein the conical member being disposed within the casing with its cylindrical part lying within the cylindrical member carried by the rotatable shutter, means for supporting the conical member on the end plate, and a fuel sprayer mounted in the end plate as set forth.
- 130 13. In apparatus for use in the burning of liquid fuel the combination of a conical casing forming an air box and having in its wall openings through which air can enter, a conical shutter rotatably mounted on the casing and serving to adjust the size of the openings in the latter, a conical shield mounted at the smaller end of the casing and extending over the openings in the latter, a fixed plate which closes the outer end of the casing and has air inlet openings therein, a rotatable shutter by means of which the size of these openings can be adjusted, a hollow conical member disposed within the casing and carried by the end plate at a distance therefrom, a fuel sprayer mounted in the end plate in such a position that the spray therefrom impinges on the inner surface of the hollow conical member, and means for adjusting the position of the conical member relatively to the fuel sprayer and the casing, as set forth.

ings, a plate which closes the outer end of the casing and has air inlet openings therein, means for adjusting the size of these openings, a hollow conical member having 5 at one end a cylindrical part with openings therein the member being disposed within the casing with its cylindrical part directed towards the end plate, means for supporting the conical member on the end plate, 10 means for adjusting the size of the openings in the cylindrical part of the conical member, a fuel sprayer mounted in the end plate, and means for adjusting the size of the conical member relatively to the fuel 15 sprayer as set forth.

8. In apparatus for use in the burning of liquid fuel the combination of a conical casing forming an air box and having in its wall openings through which air can enter, 20 a conical shutter rotatably mounted on the casing and serving to adjust the size of the openings in the latter, a fixed plate which closes the outer end of the casing and has air inlet openings therein, a hollow conical 25 member having at one end a cylindrical part with openings therein the member being disposed within the casing with its cylindrical part directed towards the end plate, means for supporting the conical member 30 on the end plate, means for simultaneously adjusting the size of the openings in the end plate and the size of the openings in the cylindrical part of the conical member, a fuel sprayer mounted in the end plate, and 35 means for adjusting the position of the conical member relatively to the fuel sprayer as set forth.

9. In apparatus for use in the burning of liquid fuel the combination of a conical 40 casing forming an air box and having in its wall openings through which air can enter, a conical shutter rotatably mounted on the casing and serving to adjust the size of the openings in the latter, a fixed plate 45 which closes the outer end of the casing and has air inlet openings therein, a rotatable shutter by means of which the size of these openings can be adjusted, a cylindrical member mounted on and rotatable with this 50 shutter and projecting into the casing this member having openings in it, a hollow conical member having at one end a cylindrical part with openings therein the conical member being disposed within the casing 55 with its cylindrical part lying within the cylindrical member carried by the rotatable shutter, means for supporting the conical member on the end plate, a fuel sprayer mounted in the end plate, and means for adjusting 60 the position of the conical member relatively to the fuel sprayer as set forth.

10. In apparatus for use in the burning of liquid fuel the combination of the combustion chamber of a steam generator having 65 an opening through the wall of the generator

casing leading into this chamber, an annulus of fire brick disposed in the opening leading into the combustion chamber the inner edge of the fire brick being bevelled off in both directions so as to be V-shaped in cross section, 70 a conical casing forming an air box mounted on the generator wall around the opening leading into the combustion chamber this air box having in its wall openings through which air can enter, a conical shutter rotatably mounted on the casing and serving to adjust the size of the openings in the latter, a fixed plate which closes the outer end of the air box and has air inlet 75 openings therein, means for adjusting the size of these openings, a hollow conical member disposed within the casing and carried by the end plate in a position intermediate between this end plate and the fire brick annulus, a fuel sprayer mounted in the end plate, and means for adjusting the position of the conical member relatively to the fuel sprayer as set forth.

11. In apparatus for use in the burning of liquid fuel the combination of a conical 90 casing forming an air box and having an annular step in its wall with openings through the part below the step through which air can enter, a conical shutter rotatably mounted on that portion of the casing which lies 95 between the step and the smaller end thereof this shutter serving to adjust the size of the openings in the casing, a conical shield mounted at the smaller end of the casing and extending over the openings in the latter, a fixed plate which closes the outer end of the casing and has air inlet openings therein, a rotatable shutter by means of which the size of these openings can be adjusted, 100 a hollow conical member disposed within the casing and carried by the end plate at a distance therefrom, a fuel sprayer mounted in the end plate, and means for adjusting the position of the conical member relatively to the fuel sprayer as set forth.

12. In apparatus for use in the burning of liquid fuel the combination of the combustion chamber of a steam generator having an opening through the wall of the generator casing leading into this chamber, an annulus 110 of fire brick disposed in the opening leading into the combustion chamber the inner edge of the fire brick being bevelled off in both directions so as to be V-shaped in cross section, a conical casing forming an air box 115 mounted on the generator wall around the opening leading into the combustion chamber this air box having an annular step in its wall with openings through the part below the step through which air can enter, a conical shutter rotatably mounted on that portion of the casing which lies between the step and the smaller end thereof this shutter serving to adjust the size of the openings in the casing, a conical shield mounted at the 120 130

smaller end of the casing and extending over the openings in the latter, a fixed plate which closes the outer end of the casing and has air inlet openings therein, a rotatable shutter 5 by means of which the size of these openings can be adjusted, a cylindrical member mounted on and rotatable with this shutter and projecting into the casing this member having openings in it, a hollow conical member having at one end a cylindrical part with 10 openings therein the conical member being disposed within the casing in a position in-

termediate between the end plate and the fire brick annulus and with its cylindrical part lying within the cylindrical member 15 carried by the rotatable shutter, means for supporting the conical member on the end plate, a fuel sprayer mounted in the end plate, and means for adjusting the position of the conical member relatively to the 20 fuel sprayer as set forth.

In testimony whereof I have signed my name to this specification.

ANDREW FORSTER.
